UNITED STATES PATENT OFFICE.

JOHN F. OHMER AND HARRY J. SIBLEY, OF DAYTON, OHIO, ASSIGNEES TO OHMER
FARE REGISTER COMPANY, OF DAYTON, OHIO, A CORPORATION OF NEW YORK,
(INCORPORATED IN 1902.)

TRANSFER-ISSUING MACHINE.

1,210,973.

Specification of Letters Patent.

Patented Jan. 2, 1917.

Application filed December 13, 1915. Serial No. 66,482.

To all whom it may concern:

Be it known that we, JOHN F. OHMER and HARRY J. SIBLEY, citizens of the United States, residing at Dayton, in the county of 5 Montgomery and State of Ohio, have invented certain new and useful Improvements in Transfer-Issuing Machines; and we do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to certain new and useful improvements in transfer or ticket issuing machines such as is described and claimed in our pending application, filed 20 October 2, 1915, Serial Number 53,750.

The present improvements relate to certain new and useful improvements for permitting a free flow or feeding movement of the transfers or tickets from the machine, 25 and to means which compels the proper withdrawal of the severed transfers whereby a complete and satisfactory issuance of each transfer from the machine is insured.

The invention consists of a discharge 30 spout or mouth piece extending forward from the machine and adapted to receive a paper strip, and by having a finger opening therein the transfer is accessible and is easily removed.

The invention consists, furthermore, of a 35 plate which lies in the mouth of the machine and moves out and in to cover and uncover each transfer or ticket as it issues from the machine. The said plate moves outwardly 40 in guides each time a transfer is printed, and simultaneously with the feeding out or issuance of such transfer the said plate is moved to its normal or inward position to enable the transfer to be grasped in the center of its exposed end.

In the accompanying drawings which 45 illustrate our said improvements, Figure 1 is a vertical section of the transfer printing and issuing machine substantially as it is 50 shown in our former application with parts omitted therefrom that are not essential to an exposition and understanding of the present improvements which are shown therein; Fig. 2 is a front elevation of the

upper portion of the machine or that portion from which the transfer or ticket is projected or fed to a position to be taken hold of by the fingers; Fig. 3 is a top plan view of the parts as shown in Fig. 2; Fig. 4 is a detail view of the transfer feeding devices and severing devices; and Fig. 5 is a detail view of elements of the paper feeding devices.

Referring more particularly to the drawings, similar reference characters indicate corresponding parts.

Referring more particularly to Fig. 1 of the drawings, 1 and 2 designate the side frame plates which are united to a base 3 from which downwardly extends an apertured boss 4 supported upon a column 5. The side frame plates 1 and 2 are suitably connected by a cross frame 6 upon which the printing wheels are mounted and a plate 7 on which the paper severing means is mounted. 70 The cross frame 6 is provided with type wheel 8 and other type wheel 10, the former type wheel being on shaft 11 and the latter type wheel being on shaft 9, both shafts being suitably journaled in the frame work of 75 the machine.

12 designates a sleeve of the spool upon which the paper strip is wound and from which are printed the transfers or tickets. This sleeve receives a spindle 13 and the ends 80 of said sleeve have disks 14 between which the roll of paper is confined. The web 16 from said roll is led in contact with the roller platen 17 which is mounted upon swinging plates 18, the shaft 19 of which is 85 mounted in adjustable bearings on a vertically movable printing frame 15. The printing frame 15 has projections 20 which carry upper and lower anti-rollers 21. These rollers 21 travel in vertical races 22 which are 90 inclosed by guides 23 attached to the side plates 1 and 2. The type are inked by an inking roller 24 which is mounted on a shaft journaled in side plates 25 which are pivoted on the shaft of the roller platen. Pins 100 26 are mounted in the races 22 and engage the upper roller 21 to shift the frame 15 and the platen roller carried thereby to move said platen roller from the type wheels after each impression is made.

27 and 28 designate feed rollers through which the web of paper is fed. The shaft 29 of the upper feed roller 27 is journaled in the ends of

slides 31 which move in guides 31^a. The shaft 30 of the lower feed roller is journaled in the side plates 1 and 2 and carries a pinion 32 which meshes with a gear 33. The shaft 34 of the gear 33 is journaled in a frame 35. The pawl 36 is carried by the gear 33 and engages a ratchet 37 on the shaft 34. A pinion 38 to which the ratchet 37 is rigidly secured is mounted on the shaft 34. A vertically movable rack 39 engages the pinion 38, said rack 39 being actuated from the printing frame 15 of the printing mechanism. The said frame 15 carries a projection 40 which alternately engages upper and lower shoulders 41 on the lower end of the rack and thus the rack is reciprocated according to the movement of the frame 15.

The printing frame 15 is operated from a foot-treadle which is not shown in the drawings nor is it necessary to describe the machine in detail. The manner of operating the same is fully shown and described in our pending application. The various printing wheels and the manner of their operation is also there fully described. The means for cutting the strip of paper into tickets or transfers is also fully described in our pending application. It is here necessary to say that it consists of a knife or blade 42 which is slidably mounted on the cross plate 7 and is movable in guides 43. The lower edge 44 of the opening 45 in the plate 7 co-operates with said knife in cutting the paper into definite lengths to make the transfers or tickets which have previously been printed in the machine. Springs 46 draw the knife downwardly across said opening, said springs being connected to the knife at one end and to the cross plate 47 at the other end. A crank 48, shown in dotted lines in Fig. 1, elevates the knife against the tension of the springs. The crank 48 is mounted upon a shaft 49 having bearings 50 said bearings being mounted upon the plate 7. A crank 51 is mounted on the shaft 49 and is operated thereby. A projection 53 on the vertically movable printing frame 15 directly engages the crank 51 and operates the same. When the knife or blade 42 is elevated by the crank 48, it is held in an elevated position by a latch 52 pivoted on the shaft 11. The end 54 of the crank 51 is engaged by said latch 52. The extended end 55 of the latch 52 is adapted to be engaged by a stud 56 on an arm 57 carried by the printing frame 15. When said printing frame 15 reaches its lowermost position, the stud 56 engages the extension 55 and rocks the latch 52 and thereby releases the knife 42 so that the springs 46 and 59 will draw said knife and the clamping plate 58 in the direction of the paper which is to be cut to form the transfer. When the paper is thus severed, the transfer made therefrom is held at its end

by the cross plate 47 and a clamping plate 58, and may be drawn out by the passenger. The clamping plate 58 is movable in the guides 43 and is controlled by the springs 59 and the crank 48, said clamping plate being elevated and lowered simultaneously with the knife 42. When the paper strip is fed by the feed rollers 27 and 28 preparatory to each cutting operation, it enters the delivery mouth 60 formed by upper and lower transverse mouth pieces 61 and 62, the former of which is secured across the upper front of the casing to the side plates 1 and 2 and the latter of which is secured to a door 73 of the casing. The said mouth pieces 61 and 62 project outwardly a substantial distance beyond the opening 60 through which the transfers are removed and the central portions of said mouth pieces are cut away at 74 in a manner to expose each transfer in a position to be caught by the fingers of the passengers for whom they are issued. As the cut-away portion 74 is at the center of the mouth pieces 61 and 62, the passenger is compelled to grasp the ticket or transfer in the center which insures its proper withdrawal. The lower mouth piece 62 is constructed to support the transfers in a convenient manner after they are issued. A slideable guard plate 63 is arranged to slide out and in immediately below the upper mouth piece. Guides 64 are provided in the upper mouth piece for this plate. As shown in Fig. 1, the plate 63 is in its inner position which is the position it is in preparatory to advancing or feeding a transfer to the position to be caught by the fingers. The said plate is moved outwardly from this position at the end of each upward movement of the printing frame 15 and before the ticket is issued, and is moved inwardly after the ticket is issued when the frame 15 reaches the limit of its downward movement. Such movement is given said plate from an arm 65 which is slotted at its free end to loosely fit over a cross pin 66 on a bracket 67 which is secured to said plate 63. The arm 65 is fixed to a shaft 68 in the side plates of the frame. To an end of this shaft 68 there is fixed an angular lever 69 having an elongated slot 70 therein. The crank 51 hereinbefore referred to as being on shaft 49 carries a stud 71 which projects through a curved slot 72 in the adjacent side plate 2 and into the slot 70 of the lever 69. It will, therefore, be seen that a movement of the crank 51 from the position shown in Fig. 4 will rock the shaft 68 to project the guard plate 63 outwardly. The crank 51 is elevated from the printing frame 15 by the vertical projection 53 carried on the vertically movable printing frame 15. The arm 51 is moved to its lower position and therewith the plate 63 is moved to its inner position simultaneously with 130

the descent of the knife 42 and clamping plate 58 through the action of the springs 46 and 59 and the crank 48 and shaft 49.

It will be apparent from the foregoing 5 description that the paper strip cannot be caught hold of and torn; in other words, it is inaccessible to the fingers until the printing and severing of each transfer or ticket is completed and it is in a position to be 10 taken possession of by the passenger.

Having described our invention, we claim:

1. In a machine of the character specified, means for intermittently feeding a strip of paper, means for cutting said strip of paper 15 at the end of each feeding operation thereof, and a plate movable to a position to cover the advanced end of said strip of paper simultaneously with each feeding operation and to a position to uncover the same at the 20 completion of the cutting operation.

2. In a machine of the character specified, means for intermittently advancing a strip of paper from a roll, a guard plate adapted to cover the advanced end of said paper strip 25 movable to such position simultaneously with the operation of the paper advancing means, a knife adapted to cut said paper strip after each advancing operation, and means actuated during the cutting movement 30 of said knife to move the guard plate to a position to uncover the severed transfer and permit of its removal.

3. In a machine of the character specified, a casing having a discharge spout, intermittent paper feeding devices adapted to feed a strip of paper into said spout, means adapted to cut said paper at the end of each feeding operation, and means actuated before and after said paper feeding devices are 40 operated to guard the end of the paper in said spout before it is cut and to enable access thereto after it is cut.

4. In a machine of the character specified, a casing having a discharge spout, paper 45 feeding means adapted to feed a strip of paper into said spout, severing means actuated subsequent to said feeding means to cut said paper, and means actuated before and after said feeding means is operated to prevent

the withdrawal of the paper from said discharge spout until after it is cut.

5. In a machine of the character specified, a casing having a discharge spout adapted to receive a paper strip, means for intermittently feeding said paper into said spout, a 55 plate movable in and out of said spout to guard the paper until it is cut, means for cutting said paper when it is advanced into said spout, and means for actuating said paper cutting means and said plate before and 60 after said paper cutting means is operated.

6. In a machine of the character specified, a casing having a discharge spout adapted to receive a paper strip, means for intermittently advancing said paper into said spout, 65 a plate movable in and out of said spout to prevent the paper being pulled out of said spout until it is cut, paper cutting devices, crank and rock-shaft connections between said plate and cutting devices, and means 70 for actuating said cutting means and therewith the crank and shaft connections.

7. In a machine of the character specified, a casing having a ticket discharge opening inclosed by two outwardly projected lips, 75 said lips having centrally disposed finger openings and the lowermost one of said lips having a rearwardly and downwardly inclined portion forming the throat of said opening, paper feeding devices adapted to 80 feed a strip of paper through said throat and into said opening, a knife for cutting each length of paper fed into said opening, and a plate within said opening movable horizontally to an outer position while the 85 paper is being fed into said opening and to an inward position to expose the end of the ticket after the paper has been fed into said opening and severed, substantially as specified.
